TUMBLER OR THE LIKE

Jerome Lewis, 230 5th Ave., New York, N.Y.

Filed Apr. 15, 1963, Ser. No. 74,448

Term of patent 14 years

(Cl. D36—8)

FIG. 1

FIG. 3

FIG. 1 is a side elevational view of a tumbler or the like embodying my new design;

FIG. 2 is a front perspective view looking downward thereon; and

FIG. 3 is a bottom plan view thereof.

The design is characterized by a mottled surface extending over the entire outer surface in combination with alternating bands of contrasting colors, bands of the same color being of the same width, said contrasting bands being in the width ratio of 3:1 and being uniformly spaced apart by intervening substantially transparent bands of uniform width all applied in the pattern shown.

I claim:

The ornamental design for a tumbler or the like, as shown and described.
